UNITED STATES PATENT OFFICE.

ARTHUR M. PELLETREAU, OF KALAMAZOO, MICHIGAN.

POSTAL ENVELOP.

SPECIFICATION forming part of Letters Patent No. 723,911, dated March 31, 1908.

Application filed March 17, 1902. Serial No. 98,611. (No model.)

To all whom it may concern:

Be it known that I, ARTHUR M. PELLETREAU, a citizen of the United States, residing at the city of Kalamazoo, in the county 5 of Kalamazoo and State of Michigan, have invented certain new and useful Improvements in Postal Envelops, of which the following is a specification.

This invention relates to improvements in 10 envelopes or postal wrappers.

As the postal system is conducted at present a large force of employees, at a large expense to the Government, are required to cancel the stamps.

15 The objects of this invention are to provide an improved postage envelop in the use of which the sender in writing the address will cancel the stamp or postage, and one in which the opening of the envelop or wrapper 20 will also destroy the stamp or postage, thus doing away with cancellation of the stamp by the Post-Office Department and also preventing fraud.

Further objects will definitely appear in 25 the detailed description to follow.

I accomplish the objects of my invention by the devices and means described in the following specification.

The invention is clearly defined and pointed 30 out in the claims.

A structure embodying the features of my invention is fully illustrated in the accompanying drawing, forming a part of this specification, in which the figure illustrated is a 35 detail plan view of an envelop-blank embodying the features of my invention.

Referring to the lettered parts of the drawing, A represents the body or face portion of the envelop, having flaps a to form the back 40 portion and seal the same. Upon the face of the envelop is printed or otherwise produced a suitable stamp B. This stamp is preferably of a size that covers a considerable portion of the face of the envelop and is 45 preferably placed thereon in a central position. Extensions b extend from the stamp across the flaps a and form a band when the envelop is folded across the back of the same, so that it is impossible to sever a flap in opening without destroying the stamp, thus pre-

venting a fraudulent reuse of the envelop, in addition to the stamping of the sending and receiving dates on the envelop, as is now customary.

I prefer to print on the extensions b the 55 words "United States postage" and a figure or words representing the value of the particular stamp, so that when the envelop is sealed these words and figures will appear on the back of the envelop and also the value 60 thereof. This is not an essential, however, to procure a practical structure, and the extensions b may be in any form desired.

While I have illustrated the stamp in stereotyped form, it is apparent that any form may 65 be used and also that it is not necessary that the stamp should cover as much of the face portion of the envelop as is illustrated, a very small stamp being all that is necessary in view of the extensions b.

Having thus described my invention, what I claim as new, and desire to secure by Letters Patent, is—

1. In a postal envelop, the combination of a front or body portion, having flaps to form 75 the back portion and to seal the same; a stamp printed on the front portion with extensions therefrom across said flaps; characters on said extensions to represent the value of the postage, for the purpose specified. 80

2. In a postal envelop, the combination of a front or body portion, having flaps to form the back portion and to seal the same; a stamp printed on the front portion with extensions therefrom across said flaps bearing 85 matter indicating value, for the purpose specified.

3. A postal wrapper having a stamp printed on the writing-space thereof, with extensions to entirely encompass the wrapper whereby 90 the stamp will be canceled and destroyed by use, said extensions bearing matter indicating value.

In witness whereof I have hereunto set my hand and seal in the presence of two witnesses. 95

ARTHUR M. PELLETREAU. [L.S.]
